UNITED STATES PATENT OFFICE

157,145

COMBINATION TUMBLER AND TOOTH-BRUSH HOLDER

Gustav A. Hallenscheid, Los Angeles, Calif., assignor to Hall-Mack Company, Los Angeles,
Calif., a corporation of California

Application December 27, 1948, Serial No. 150,381

Term of patent 14 years

(Cl. D4—3)

To all whom it may concern:

Be it known that I, Gustav A. Hallenscheid, a citizen of the United States, residing at Los Angeles, in the county of Los Angeles and State of California, have invented a new, original, and ornamental Design for Combination Tumbler and Toothbrush Holder, of which the following is a specification, reference being had to the accompanying drawing, forming a part thereof.

The figure is a perspective view of a combination tumbler and toothbrush holder, showing my new design.

I claim:

The ornamental design for a combination tumbler and toothbrush holder, as shown.

GUSTAV A. HALLENSCHEID.
